UNITED STATES PATENT OFFICE.

ANTONINO GIUFFRÉ, OF REVERE, MASSACHUSETTS.

STOVE, HOT-WATER AND STEAM HEATER, AND FURNACE.

1,149,806.

Specification of Letters Patent. Patented Aug. 10, 1915.

Application filed February 1, 1915. Serial No. 5,377.

To all whom it may concern:

Be it known that I, ANTONINO GIUFFRÉ, subject of the King of Italy, residing at Revere, county of Suffolk, State of Massachusetts, have invented a certain new and useful Improvement in Stoves, Hot-Water and Steam Heaters, and Furnaces, of which the following is a specification, reference being had thereto to the accompanying drawings.

The invention relates to an improvement in heating apparatus in which coal is employed as fuel.

It is a very common practice for people who use coal as a fuel in stoves, furnaces, steam or hot-water heaters, etc., to sift the ashes in order to save the partially consumed coal which passes through the grate. So far as known to me it has heretofore been customary in such cases to remove the unsifted ashes from the ash pit after the fire has been shaken down or the grate has been turned to dump the contents of the fire pot into the ash pit and to carry them to a sifter which is entirely independent of the stove or furnace and is located at any convenient place apart from the heater. This necessitates handling the ashes twice, once to carry them to the sifter and again to empty the ashes after being sifted, if they are sifted into a barrel, and if sifted in the open air the ashes fly about into the face and over the person sifting and are a cause of much annoyance.

The object of the present invention is to combine with the stove, furnace or other heater a sifter whereby the ashes may be sifted before removal from the stove or furnace so that the sifted ashes may be removed separately from the coarse siftings or pieces of coal which are to be burned again, and thus no sifting is required outside of the heating apparatus. The several features of the invention will be more particularly set forth hereinafter.

The invention will be fully understood from the following description taken in connection with the accompanying drawings and the novel features thereof will be pointed out and clearly defined in the claims at the close of the specification.

The invention is illustrated in the drawings as embodied in a stove or kitchen range but as above set forth it is adapted to be used in connection with a furnace or a steam

or hot-water heater or other coal burning heating apparatus.

In the drawings,—Figure 1 is a perspective view partly broken away of a stove or range embodying the invention and showing some of the interior parts in dotted lines, the stop device for the sifter being in normal position to prevent rocking of the sifter. Fig. 2 is a front elevation of the stove shown in Fig. 1 partly broken away and with the doors to the fire pot and sifter chamber and drawer or pan chamber removed. This view also shows the sifter partially turned as in the act of rocking the sifter and with the stop device turned up into inverted position from that shown in Fig. 1 as is intended during the sifting. Fig. 3 is a view from the same position as Fig. 2 somewhat more broken away and showing the ash pan and the stop device for the sifter removed and showing the sifter itself completely turned over as when the sifter is turned to dump the coal into the coal pan. Fig. 4 is a vertical section longitudinally of the sifter. Fig. 5 is a detail perspective view of the sifter. Fig. 6 is a detail perspective view of the coal pan. Fig. 7 is a detail view of the stop device.

Referring now to the drawings,—1 represents the fire pot or chamber of the stove within which is a grate 2 of any suitable form of construction and so mounted that it may be turned to dump the contents of the fire pot into the chamber beneath. The said grate is shown as being provided with a journal 3 at the front end and a journal 45 at the rear end by which the said grate is journaled in bearings in the front plate 21, and back plate 46. The front end of the journal 3 terminates in a squared portion 5 to receive a key to turn the grate in well known manner.

Below the grate 2 is a chamber 6 within which is contained the sifter 7, the said chamber 6 being virtually a downward continuation of the fire chamber 1 from which it is separated only by the grate 2. The said sifter 7 is preferably in form a segment of a cylinder extending lengthwise beneath the grate for the full length of the grate. The body of the cylinder is composed of any suitable wire mesh of suitable strength and fineness of mesh to serve as an ash sifter. Its opposite ends are formed by the heads 8, 9 respectively which consist of

plates of metal, and preferably there are longitudinal bars or rods 10, 11 which form the upper longitudinal edges of the frame to which the cross wires of the sieve are connected, the longitudinal wires of the sieve being connected with the heads 8, 9. Preferably also there are one or more longitudinal strengthening rods or strips 12 intermediate the longitudinal rods 10 and 11 and the cross wires of the sieve will preferably pass through holes in the intermediate strengthening rod 12. The heads 8, 9 of the sifter are provided with the cylindrical journals 13, 14 by which the sifter is journaled in bearings in the front and rear walls of the sifter chamber.

The sifter chamber 6 is formed with outwardly bulging side walls, each preferably made on the arc of a circle of a somewhat larger radius than the radius of the sieve to allow for the rotary movement of the sieve within the chamber. The wall 15 on that side of the sifter chamber which is toward the inner portion of the sieve, that is, on the oven side, as shown in the type of stove illustrated in the drawings, is made close enough to the side of the sifter to merely allow a sufficient clearance to permit the passage of small pieces of coal which may get through the sides of the sifter, say a clearance of perhaps a half or three quarters of an inch. The other side wall 16, is made with an extension bulge so as to provide a space 17 of some width between the circumference of the sifter and the said wall 16 to afford a passageway for the lumps of coal when dumped from the sifter after the ashes have been sifted, as will be herein-after explained. The sifter will be of segment shape, as already mentioned, and will be preferably of somewhat more than a half cylinder, the journals 13, 14 of the sifter being in the line of the axis of the cylinder of which the sifter is a segment. The chord 18 which is measured by the cross section of the top or opening of the sifter should be about the same length as the width of the bottom of the fire chamber or the cross section of the grate. In order to guide the ashes from the grate into the sifter and to prevent the ashes from falling down around the outside of the sifter there are provided longitudinally of the sifter the inwardly sloping guides 19, 20 just below the grate 55 and just above the entrance to the sifter.

The front wall in which the sifter is journaled consists of a removable plate 21 which covers the end of the fire pot and of the sifter chamber, being of a somewhat banjo shape as shown in Fig. 2 of the drawings. It is secured by screws 22 which pass through holes in the said plate and screw into holes in one of the walls of the stove and by a button 49. The said front plate 21 is made removable for the purpose of con-

venience in assembling the parts. The rear wall 46 of the stove in which the rear end of the sifter is journaled is not necessarily removable. The front journal 13 passes through a hole in the said bearing plate 21 and is provided with a squared portion 23 on its outer end to receive the key by which the sifter is rotated. It should preferably be made of the same size as the squared end 5 of the grate journal so that the same key 75 may be used in turning the grate and the sifter.

Below the sifter chamber 6 is another chamber 24 opening directly out of the sifter chamber which corresponds in location somewhat to that of the ordinary ash pit but which on account of the use to which it is put will be herein referred to as the drawer chamber or pan chamber. This drawer or pan chamber contains at least 80 one pan and preferably two pans 25, 26 one above the other, the upper pan 25 being for the purpose of receiving the sifted ashes and the lower pan 26 being for the purpose of receiving the coal dumped from the sieve 90 after the sifted ashes have been removed by taking out the pan 25. It is possible to get along with the use of one pan only which shall be used both as an ash pan and a coal pan if after the ashes have been sifted 95 the said pan is taken out and emptied of the ashes before the sifter is turned to dump the coal and then the pan is put back in place and the sifter is turned and the coal dumped into the same pan, but this is not 100 so convenient as to provide two pans. The upper pan 25 slides on cleats or ledges 27 and is supported at the front on a cross cleat or ledge 28. The bottom pan 26 may slide on the bottom of the chamber or on 105 any suitable ways 51. These pans should preferably be made of sheet metal comparatively thin so as to make them as light as possible consistent with strength, and in order to avoid the collection of ashes on the 110 top of the side walls of the pan the side walls 29 should preferably be made to bow inward, as shown in the drawings, the upper edge of the said walls being thin and the walls being curved inward, thereby practically preventing any lodging of the ashes upon the top of the side walls of the pan. The top and bottom edges of the said curved side walls will fit as close to the side walls 47 of the drawer chamber as is consistent 115 120 with allowing the pans to slide in and out. The front 48 of the pan, however, will be finished square so as to make a closed front. The interior of the drawer chamber is of somewhat greater width than the diameter 125 of the sifter chamber so that the outwardly flaring upper edges of the side walls 29 of the pan will form an entrance wider than the sifter chamber and thereby insure the ashes going into the pan. There are also 130

preferably provided converging guides 52 to more surely prevent the ashes from falling outside of the pan.

As already mentioned, a stop device is provided which when the parts are in their normal position will prevent the sifter from being rotated and which may be adjusted so as to allow a limited range of movement of the sifter to sift the ashes and which may be moved out of the way so as to permit a complete turning over of the sifter to dump the coal after the ashes are sifted. Various means may be provided for this purpose. The special means shown in the drawings are as follows,—Mounted on the squared end 23 of the front journal of the sifter is a finger or tail member 30 which hangs down normally in a vertical position, as shown in Fig. 1. This tail piece may be secured to the journal in any suitable way but as shown it is formed with a socket head 31 which fits over the squared end 23 of the journal and is secured by a clamp screw 32. Rod 33 is hung in suitable supports or hooks 24 on the front side of the plate 21 at some distance below the journal of the sifter in such manner that the said rod 33 may be turned in its supports.

In order that the rod 33 may not slide endwise out of its bearings in the hooks 34, it is provided at each end with a head 30.

Projecting from one face of the rod are the two ears 35 and when the sieve is in its normal position, as shown in Fig. 1, the said rod 33 should be set so that the said ears will extend upward. These ears are so located that the tail member 30 when hanging vertically downward in the normal position of the sifter will extend between the said two ears 35, 35 which are spaced only a short distance apart from each other so that they serve as stops against which the tail member 30 will strike before the sifter can be turned on its axis any distance and therefore they maintain the sifter in its normal unturned position. Projecting from said rod 33 on the opposite side from the ears 35, 35 are two pins 36, somewhat longer and spaced farther apart than the ears 35, 35 and which will point in a downward direction when the ears 35, 35 point in an upward direction, as in Fig. 1. The rod 33 may be readily turned by the hands of the person operating the device so that the ears 35, 35 will point downwardly and the pins 36, 36 will point upwardly, as shown in Fig. 2, and when in this position the sifter is permitted to be turned or rocked on its axis a limited distance until the tail member 30 strikes one or the other of the two pins 36, 36, as shown in Fig. 2. It is preferable to turn the rod 33 far enough so that the pins 36, will incline backward far enough for their upper ends to rest against the plate 21, so as to steady the rod 3. This

is the position which the rod 33 should occupy when it is desired to rock the sifter to sift the ashes. Said rod may also be lifted out of its supports and removed so that neither the stops 35 nor the stops 36 will be in engaging position and thus permit the sifter to be turned up-side-down as shown in Fig. 3.

In order to provide a side support for the pins 36 so that they may not be broken when the sifter is being rocked and the tail member strikes against the stop pins 36, the bearing plate 21 is formed with a pair of lugs 37 projecting from the outer face thereof spaced apart slightly more than the pins 36 so that when the rod 33 is turned to bring the pins 36, 36 into an upwardly extending position said pins will bear respectively against the inner faces of said lugs 37 as is shown in Fig. 2. When the sifter is being worked it is preferable to give it a rocking stroke alternately in each direction far enough and with sufficient force to cause the tail member 30 to strike sharply against the stop pins 36, thereby causing the ashes to fall more rapidly through the sifter.

When the sifter has been agitated sufficiently to cause the ashes to pass into the pan 25 beneath it the pan 25 should be removed. This leaves a free passage through the upper portion of the pan chamber previously occupied by the pan 26 and down into the open top of the coal pan 23. Then the stop rod 33 should be moved so as to place the stop ears 35 and fingers 36 out of position to be engaged by the tail member 30, this preferably being done by lifting the stop rod entirely off of the supporting hooks 34, laying it one side, and then by means of the key the sifter will be turned up-side-down so that the coal remaining in the sifter will be dumped out into the pan 26 and the pan 26 can then be removed at any time desired. It may be left for the time being in its seat and taken out to remove the coal afterward if desired. As soon as the coal is dumped from the sifter the sifter should be turned back into its normal position and the stop rod should be placed afoe in position, as shown in Fig. 1.

In turning the sifter to dump the coal it should be turned in the direction to bring the open top of the sifter around toward the passageway 17 in the swelled front part of the sifter chamber, that is, to the left as viewed in the drawings.

In order that the tail member 30 shall not strike against the lugs 37 during the dumping of the sieve after the stop rod 33 has been removed said lugs 37 and tail member 30 are so proportioned and arranged that the tail member 30 will swing clear of the said lugs 37 when the sifter is rotated for emptying it.

The pans 25, 26 should each be provided

4
 with a handle or draw pull 38 so that they can be pulled out like a drawer from a desk and should also be provided with a bail 39 which serves as a handle with which to carry 5 the pan when it has been removed. This bail, however, should be a drop bail so that when the pan is in its position in the pan chamber it will not project above the top edge of the pan. To this end the sides of 10 the pan are formed with notches 40, 40 in the upper edges into which the bail will drop when turned down, the bail being pivoted at its connection with the pan so that it may be dropped down as described. In 15 order that the coal pan may be used to conveniently pour the contents thereof directly into the stove without first dumping it into a coal hod the rear end of the pan is preferably formed with a rearwardly inclined wall 41 as shown in the drawings.

20 A hinged door 42 is provided which covers the entire front of the plate 21 which covers the end of the fire chamber and the sifter chamber, being hinged at 43, 43 to the 25 frame of the stove and is swelled outwardly, as is clearly shown in Fig. 4 so that it shall cover the ends of the grate journal and sifter journal and the stop device. The front 30 of the drawer chamber is also closed by a hinged door 44 which is swelled outwardly in similar manner to the door 42 so as to cover the front ends and draw pulls of the 25, 26.

35 While I have shown and described the sifter as being of a semi-cylindrical form and vibrated by a rocking movement, I do not intend to be limited to the particular form of sifter or to the particular mode of vibration.

40 So far as I am aware I am the first to provide within the heater a sifter intermediate between the fire chamber and the ash pan so that the ashes have to pass through the sifter after leaving the fire chamber and before 45 reaching the ash pan and I intend to have the claims broadly cover such a combination.

By reason of the sifter, the stove is somewhat higher than would otherwise be necessary. This affords space for a warm closet 50 53 below the oven 54 and above the bottom closets 55.

55 In the use of the apparatus the grate may be shaken in any well known way and if this is done while the fire is still alive the burning coal which is already left in the fire pot after the grate has been shaken will serve as a stop to prevent the dust rising through the grate during the sifting of the ashes and therefore the ashes may be sifted 60 immediately after shaking the grate without any trouble arising therefrom. If, however, the fire has gone out before the grate is shaken then the grate should first be shaken and the dead coal dumped and the contents 65 should be allowed to remain in the sifter un-

til such time as the new fire is started. Then after the new fire is started the contents of the fire pot will serve as a stop for the rising of the dust so that the ashes can be sifted.

What I claim is:

1. In a stove or other heating apparatus, a grate, a removable ash pan located at some distance below the grate, a sieve located between the said grate and the said pan to receive the coal and ashes passing 75 through the grate, means whereby said sieve may be agitated to sift the ashes into the pan beneath, a second pan normally located directly below said ash pan, and means whereby said sieve may be inverted so that 80 when the ash pan is removed the remaining contents of the sieve may be dumped into the said second pan while said second pan is in its normal position.

2. In a stove or other heating apparatus, a 85 movable grate, a removable ash pan located at some distance below the grate, a trough-shaped sieve located beneath the said grate and above said ash pan in such position that any contents of the fire pot which pass 90 through the grate will pass into the said sieve, said sieve being journaled in such manner that it may be rocked on its axis to agitate and sift the contents of the sieve and may be turned on its axis far enough to 95 dump the remaining contents of the sieve after the sifting into a receptacle beneath, and a movable stop device which has certain projections which when the stop device is in its normal position prevents the sifter from 100 being turned on its axis and which has certain other projections which when the stop device is turned into another position allow the said sifter to be rocked on its axis for a limited range of movement to permit the 105 sifter to be agitated to sift the ashes, said stop device being still further movable at the will of the operator to permit the inverting of the sifter to dump the contents there- 110 after the ashes have been sifted.

3. In a stove or other heating apparatus, a movable grate, a removable ash pan located at some distance below the grate, a trough-shaped sieve located beneath the said grate and above said ash pan in such position that any contents of the fire pot which pass 115 through the grate will pass into the said sieve, said sieve being journaled in such manner that it may be rocked on its axis to agitate and sift the contents of the sieve and may be turned on its axis far enough to 120 dump the remaining contents of the sieve after the sifting into a receptacle beneath, and a movable stop device which in its normal position prevents the said sifter from 125 being turned on its axis and which at the will of the operator is movable into a position where it permits a limited range of rocking movement of the sieve to permit it to be agitated to sift the contents thereof 130

and which may be removed out of operative position with relation to the sieve, leaving the sieve free to be turned on its axis sufficiently to invert it to dump the contents 5 thereof.

4. In a stove having a fire pot and a grate, a sifter chamber below the grate, a semicylindrical sieve having a head at each end thereof, said heads being journaled in supports at the opposite ends of the sifter chamber, a removable ash pan normally located directly below the sifter, and a second removable pan normally located directly below said 10 ash pan, the space between said 15 second pan and the sifter being open to allow the contents remaining in the sifter to be dumped into said second pan while the said pan is in its normal position by turning the said sifter into inverted position after 20 the ash pan has been removed.

5. In a stove or other heating apparatus, a grate, a removable ash pan directly below the grate, a sifting device intermediate between the grate and the ash pan, the said 25 sifter being so located with relation to the grate and the ash pan that any contents passing through the grate must pass into the sifter before it can pass into the ash pan, means for agitating the sifter so that it will 30 sift the ashes directly into said ash pan without removing the sifter or ash pan from their normal location and a second removable pan below the ash pan so located that the remaining contents of the sifter may be 35 dumped into said second pan while in its normal position by inverting the sifter after the ash pan has been removed.

6. In a stove or other heating apparatus, a grate, a sifting device below the grate into 40 which the material passing through the grate falls, a chamber in which said sifter is located, a pan chamber below the sifting device having an open top which is open to the sifter chamber and a pan located in said pan 45 chamber, said pan having two opposite side walls which are curved inwardly to form convex inside faces, the width of the pan across the top of said convex walls being the same as the width between the bottom edges 50 of said walls.

7. In a stove or other heating apparatus, a grate, a sifting device below the grate into which the material passing through the grate falls, a chamber in which said sifter is 55 located, a pan chamber below the sifting device having an open top which is open to the sifter chamber, and a pan located in said pan chamber, said pan having its side walls made of thin metal and bowed inwardly to 60 form a convex inside face, the top and bottom of said pan being of the full width of

the pan chamber, and ledges on the inner side walls of the pan chamber on which said pan is slid able.

8. In a stove or other heating apparatus, a grate, a sifting device below the grate into which the material passing through the grate falls, a chamber in which said sifter is located, a pan chamber below the sifting device having an open top which is open to the sifter chamber, and a pan located in said pan chamber, said pan having its side walls made of thin metal and bowed inwardly to form a convex inside face, the top and bottom of said pan being of the full width of the pan chamber, and ledges on the inner side walls of the pan chamber on which said pan is slid able, the front end of the pan having straight side edges and fully closing the entrance to the pan chamber. 80

9. In a stove having a fire pot and a grate, a sifter chamber below said grate, a rotatable sifter within said chamber, a movable stop device whereby when the stop is in one position the sifter is allowed to be rocked on its axis through a limited arc only but prevents its being inverted and which may be moved to permit a complete inverting of the sifter. 85

10. In a stove having a fire pot and a grate, a sifter chamber below said grate, a rotatable sifter within said chamber, a movable stop device whereby when the stop is in one position the said sifter may be held against rocking movement and which may be moved to another position thereby permitting the sifter to be rocked a limited distance only but not far enough to be inverted and which may be moved at the will of the operator to permit a complete inverting of the sifter. 95

11. In a stove having a fire pot and a grate, a sifter chamber below said grate, a rotatable sifter within said chamber, said sifter being journaled at each end thereof, a front plate covering the front end of the grate and sifter chamber, said sifter being journaled in said plate, a movable stop device mounted on said front plate whereby when the stop is in one position the said sifter may be held against rocking movement and which may be moved to another position thereby permitting the sifter to be rocked a limited distance and which may be removed to permit a complete turning of the sifter. 100 105 110 115

In testimony whereof I affix my signature, in presence of two witnesses:
